COMBINATION IGNITION LOCK

John Wesley Bennett, Oshawa, Ontario, Canada

Application June 21, 1934, Serial No. 731,665

8 Claims. (Cl. 70—53)

My invention relates to improvements in combination ignition locks, and the object of the invention is to devise a positive lock of this type which is easily operated and which cannot be tampered with, and it consists essentially of the arrangement and construction of parts as hereinafter more particularly explained.

Fig. 1 is a perspective view of my lock.

Fig. 2 is a cross sectional view through the lock 10 showing the parts in position to prevent the operation of the ignition key.

Fig. 3 is a similar view to Fig. 2 showing the parts in the position to permit the operation of the ignition key.

Fig. 4 is a sectional plan on line 4—4 Fig. 2. 15 Fig. 5 is a sectional plan on line 5—5 Fig. 2. Fig. 6 is a sectional plan on line 6—6 Fig. 2. Fig. 7 is a sectional plan taken on the plain of the lock casing face.

Fig. 8 is a sectional plan view similar to Fig. 6 20 showing the parts in position to permit the engaging of the operating stem and key stem.

Fig. 9 is a perspective detail of one of the locking discs.

Fig. 10 is a perspective detail of the member 25 connecting the operating stem with the graduated dial coacting therewith.

Fig. 11 is a perspective detail of the key stem.

Fig. 12 is a perspective detail of the operating 30 stem.

Figs. 13 and 14 are enlarged details of the central portions of Figs. 2 and 3.

Figs. 15 and 16 are enlarged sectional views 35 similar to Figs. 2 and 3 but looking in the opposite direction.

In the drawings like characters of reference indicate corresponding parts in each figure.

1 and 2 are inner and outer discs provided with central circular recesses 1^x and 2^x forming 40 a chamber. 2° are a plurality of recesses arranged around the main recess 2^x and slightly overlapping the same as clearly indicated in Fig. 5. 3 is an orifice extending through the plate 2. Centrally of each recess 2° is an orifice 3 extending 45 through the plate 2 and in axial alignment with each orifice 3 is an orifice 3^x in the plate 1. The plates 1 and 2 are secured together by screws 4.

5 are short shafts journaled in the aligned 50 orifices 3 and 3^x. Each shaft is provided with a disc 5^x fitting the corresponding recess 2°, the periphery thereof overlapping the main recess 2^x. Each disc 5^x is provided with an edge recess 5°, the edge of which coincides with the edge of the

recess 2^x. 6 is a tongue extending from the edge of the disc centrally of each recess 5°.

7 is a cylindrical casing enclosing the discs 1 and 2 provided with orifices 7^x through each of which extends a threaded extension 5' of the shaft 5 on which is screwed a knurled nut 8 for operating the shaft 5. 9 is an annular disc suitably graduated and fitting on the threaded portion 5' so as to shoulder against the end of the same and be clamped thereon by the nut 8 to turn with 10 the shaft 5. Each disc 9 may fit into a recess formed in the face of the cover 7.

The main recesses 1^x and 2^x are provided with central orifices 10 and 11 having annular recessed edges 10^x and 11^x. 12 and 13 are cylindrical members extending respectively through the orifices 10 and 11 and provided at their inner ends with annular flanges 12^x and 13^x fitting the annular recesses 10^x and 11^x.

14 are pins extending from the inner end of 20 the member 12 at diametrically opposite sides of a central guiding pin 15. The member 12 passes through the orifice 10 so as to project from the disc 1 and is provided with an annular groove 12° in which is sprung a split ring 16 25 against the face of the disc 1 securing the parts together. The member 12 is provided with a diametric slot 12' in which is secured a key 17 by means of a rivet 17^x (see Fig. 11). The member 13 is cylindrical and provided with an annular flange 13^x fitting the edge recess 11^x and from which extend pins 13° longitudinally opposite to the pins 14. The sleeve 13 is provided at its opposite end with a threaded extension 13' which, when the parts are assembled, projects 30 through the disc 2.

18 is an annular disc suitably graduated and clamped in place against the member 13 by a sleeve nut 19 screwed onto the portion 13'. 20 is a rotatable stem extending through the member 40 13 and provided at its inner end with a disc 20^x. 21 is a projection extending inward from the upper edge of the recess 2^x. 22 is a notch formed in the edge of the disc 20^x and through which the projection 21 passes when the stem 20 is moved longitudinally. The remaining notches 23 correspond in position to the projections 6 when set radially to the centre of the main recess 2^x. The opposite end of the stem 20 is provided with a reduced threaded portion 24 on which is screwed a 50 knurled nut 25 by which the stem 20 is manually rotated. The disc 20^x is provided with a limiting slot 26 into which a projection 27 extending from the base of the recess 1^x extends. The height of the pin 27 corresponds to the thickness of the 55

disc 20^x. 28 is a central orifice into which the guiding pin 15 extends and 29 are orifices located on diametrically opposite sides of the central orifice 28 in which the pins 13° and 14 engage alternately.

When the parts are in the position shown in Fig. 2 the disc 20^x is turned freely within the recess 2^x by means of the knurled nut 25, the member 13 being also turned by means of the pins 13° located in the orifices 29 together with the disc 18 which is clamped to the member 13 by the nut 19. Unless the operator knows the combination nothing further can take place and the key 17 cannot be operated.

If it is desired to engage the key 17 to operate the ignition lock, the disc 18 is set so that the combination number is opposite the pointer 30. This operation carries the notch 22 opposite the projection 21. The knurled nuts 8 are then turned to carry their combination numbers opposite to their respective indicating pointers 31 bringing the tongues 6 opposite to the notches 23 previously located in the required position by setting of the notch 22 opposite the tongue projection 21.

When the combination is thus set the operator presses upon the nut 25 carrying the stem 20 and disc 20^x inward from the position illustrated in Figs. 2 and 13 so that the orifices 29 almost clear the pins 13° and engage the pins 14, the tongues 21 and 6 passing through the notches 22 and 23 so as to assume the position illustrated in Figs. 3 and 14. Simultaneously the projection 27 enters the slot 26 so as to limit its turning movement. When the parts are so positioned the turning of the nut 25 rotates the stem 20, disc 20^x and key stem 12 connected to the disc 20^x by the pins 14 to operate the key 17 to open or close the ignition lock. The rotation of the disc 20^x is limited to turn between these two positions by means of the slot 26 coacting with the stop pin 27.

When the disc 20^x is withdrawn to the position shown in Fig. 2 it is turned so that the notch 22 is carried out of line with the projection 21 and the discs 5^x to the positions shown in Fig. 5 so as to overlap the disc 20^x and prevent its longitudinal movement into engagement with the pins 14.

If it is desired to change the combination a suitable instrument is passed through the orifice 32 into engagement with the disc 20^x to prevent its rotation. The nuts 25 and 8 are then loosened and the discs 18 and 9 turned to any desired position to bring new numbers opposite to the pointers 30 and 31.

From this description it will be seen that I have devised a very simple form of combination lock for ignition switches which can be easily engaged by pressing on the operating nut 25 when the combination is set and which nut can be freely turned when withdrawn and the combination in the unset position so that no engagement can be made by an unauthorized person who does not know the combination.

What I claim as my invention is:—

1. A combination ignition lock comprising a lock body, a rotatable key stem and a rotatable and longitudinally movable operating stem mounted in the body in axial alignment, a graduated disc mounted concentrically with the operating stem, means for engaging the operating stem and disc when the stem is in the outward position and disengageable by the inward movement of the stem, means for engaging the operating stem with the key stem when the operating stem is in the inward position, and means for normally holding the operating stem out of en-

gagement with the key stem by the turning of the operating stem and disc to a predetermined position.

2. A combination ignition lock comprising a lock body, a rotatable key stem and a rotatable and longitudinally movable operating stem mounted in the body in axial alignment, a graduated disc mounted concentrically with the operating stem, means for engaging the operating stem and disc when the stem is in the outward position and disengageable by the inward movement of the stem, means for engaging the operating stem with the key stem when the operating stem is in the inward position, means for normally holding the operating stem out of engagement with the key stem by the turning of the operating stem and disc to a predetermined position, and a plurality of graduated supplemental discs turnably mounted in the body to be set at any predetermined position and means coacting with the supplemental discs to release the operating stem to move longitudinally when in the set position and to prevent such movement when in the unset position.

3. A combination ignition lock comprising a lock body having a central chamber, a key stem and operating stem journaled in opposite walls of the chamber in axial alignment, a disc carried on the operating stem within the chamber and having a plurality of edge notches, a member mounted in the body concentric with the operating shaft and turnable therewith, pin projections extending from the inner end of such member to normally engage the notched disc, pins extending from the key stem in axial alignment with the aforesaid pins and adapted to engage the notched disc when such disc is moved out of engagement with the pins of the member, and settable combination devices coacting with the notches of the disc for permitting when in the set position the longitudinal movement of the disc and operating shaft and preventing such movement when in the unset position.

4. A combination ignition lock comprising a lock body having a central chamber, a key stem and operating stem journaled in opposite walls of the chamber in axial alignment, a disc carried on the operating stem within the chamber and having a plurality of edge notches, a member mounted in the body concentric with the operating shaft and turnable therewith, pin projections extending from the inner end of such member to normally engage the notched disc, pins extending from the key stem in axial alignment with the aforesaid pins and adapted to engage the notched disc when such disc is moved out of engagement with the pins of the member, settable combination devices coacting with the notches of the disc for permitting when in the set position the longitudinal movement of the disc and operating shaft and preventing such movement when in the unset position, a graduated disc mounted concentric to the operating stem and turnable therewith, and a graduated disc coacting with each combination device and turnable therewith.

5. A combination ignition lock comprising a lock body having a central chamber, a key stem and operating stem journaled in opposite walls of the chamber in axial alignment, a disc carried on the operating stem within the chamber and having a plurality of edge notches, a member mounted in the body concentric with the operating shaft and turnable therewith, pin projections extending from the inner end of such

member to normally engage the notched disc, pins extending from the key stem in axial alignment with the aforesaid pins and adapted to engage the notched disc when such disc is moved out of engagement with the pins of the member, settable combination devices coacting with the notches of the disc for permitting when in the set position the longitudinal movement of the disc and operating shaft and preventing such movement when in the unset position, a graduated disc mounted concentric to the operating stem and releasably clamped thereto, and a graduated disc coacting with each combination device and releasably clamped thereto.

6. A combination ignition lock comprising a lock body having a central chamber, a key stem and operating stem journalled in opposite walls of the chamber in axial alignment, a disc carried on the operating stem within the chamber and having a plurality of edge notches, a projection extending from the wall of the chamber adapted to pass through one of said notches when the disc and operating shaft are moved longitudinally, a member mounted in the body concentric with the operating shaft and turnable therewith, pin projections extending from the inner end of such member to normally engage the notched disc, pins extending from the key stem in axial alignment with the aforesaid pins and adapted to engage the notched disc when such disc is moved out of engagement with the pins of the member, settable combination devices coacting with the notches of the disc for permitting when in the set position the longitudinal movement of the disc and operating shaft and preventing such movement when in the unset position, such combination devices each comprising a disc turnably mounted on the body and overlapping at its periphery the notched disc and having an edge recess conforming to the periphery of the notched disc and a tongue in the centre of each edge recess adapted to pass through a corresponding notch in the notched disc when

the projection of the body passes through its corresponding notch in the notched disc, a graduated disc mounted concentric to the operating stem and releasably clamped thereto, and a graduated disc coacting with each combination device and releasably clamped thereto.

7. A combination ignition lock comprising a lock body having a central chamber, a key stem and operating stem journalled in opposite walls of the chamber in axial alignment, a disc carried on the operating stem within the chamber and having a plurality of edge notches, a member mounted in the body concentric with the operating shaft and turnable therewith, pin projections extending from the inner end of such member to normally engage the notched disc, pins extending from the key stem in axial alignment with the aforesaid pins and adapted to engage the notched disc when such disc is moved out of engagement with the pins of the member, settable combination devices coacting with the notches of the disc for permitting when in the set position the longitudinal movement of the disc and operating shaft and preventing such movement when in the unset position, means for limiting the turning movement of the operating stem when in engagement with the key stem to correspond with turning limit of the key, such means comprising a projection extending from the bottom of the chamber, and an arc shaped slot in the notched disc into which the projection extends when the disc and key stem are in engagement.

8. In a combination ignition lock, a rotatable key stem, a rotatable operating stem in axial alignment with the key stem, visible settable means coacting with the operating stem for indicating the engaging position of the operating stem with the key stem, and means for simultaneously engaging the set operating stem with the key stem and disengaging the operating stem from the indicating means.

JOHN WESLEY BENNETT.
